Primary Examiner — Kendra Leslie Hamilton*Assistant Examiner* — Elizabeth S Struble(74) *Attorney, Agent, or Firm* — Bartholomew Law PC;
Michael Bartholomew**(57) CLAIM**

The ornamental design for a therapy cap as shown and described.

DESCRIPTION

FIG. 1 is a front, left and top perspective view of a therapy cap, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front elevation view of the therapy cap of FIG. 1, shown in condition for use for clarity of disclosure.

The broken lines in the drawings depict environmental structure that form no part of the claimed design.
